COTTON HANDLING APPARATUS

Thaddeus S. Grimes, Columbus, Ga., assignor to
The Lummus Cotton Gin Company, Columbus,
Ga., a corporation of Georgia

Application May 22, 1929, Serial No. 365,194

8 Claims. (Cl. 19—37)

My invention relates to cotton handling apparatus and particularly to a hull separator and cleaner for the treatment of dirty bolly cotton preparatory to the introduction thereof into the gin,—although the invention in its broadest aspects is not limited to the specific dual functions stated.

By way of introduction, it may be stated that a certain amount of cleaning of the cotton ahead 10 of the hull separation is desirable. However, such cleaning treatment should be just sufficient to take out the bulk of loose dirt and leaf trash, as too much cleaning at this stage encourages the hazard of shale from the burr in the lint. However, after the hull has been removed the cleaning 15 is greatly simplified and a vigorous treatment of the cotton over ample cleaning surface is very desirable.

It is, therefore, the primary object of my invention to provide a combined hull separator 20 and cotton cleaner, which can be readily installed in ginning systems of various kinds to receive the cotton from a feeder, conveyor or the like,—the initial action of my machine being to separate the hulls from the seed cotton and then subject the latter to a thorough cleaning treatment.

Another object of the invention is to provide 25 a hull separator and cleaner wherein the seed cotton is delivered from the separator to the cleaner in a thin bat whereby the cleaning process may be carried out very much more efficiently than in prior apparatus wherein the hulled seed cotton is delivered in a heavy irregular mass 30 or wad to the cleaning apparatus from a conveyor or the like,—instead of from the hull separator direct, as herein.

Another object of the invention resides in the provision of novel bypass valve means associated 40 with the inlet of the machine and whereby the cotton may be directed thereinto or passed directly to the gins,—by way, for instance,—of the belt or other distributor for feeding the seed cotton to the gins.

A further object of the invention resides in the provision of novel and improved means for maintaining a very efficient separation of hulls and trash from the cotton upon the introduction of the latter into the machine; and for positively 45 subjecting the hulls to a maximum of lint removing action for a comparatively long period of time to assure the removal of all lint from the hulls before the same are discharged.

The invention further contemplates the combination with a hull stripper roll incorporated

in the machine, of a novel peripheral surface formation thereof which effectively prevents passage of the hulls beyond said stripper roll, but at the same time avoiding the stripping back of the seed cotton.

A still further object of the invention resides in the provision of a combined hulling and cleaning machine, as characterized, wherein the hull-discharge spout or passageway is located in the path of the seed cotton as it approaches its outlet 10 and wherein moving elements of the seed cotton cleaning apparatus have means for removing the seed cotton from the line of said trash discharge spout while conveying such seed cotton toward its outlet.

The invention also resides in certain novel features of construction, combination and arrangement of the various parts and in certain modes and methods of operation, all of which will be readily understood and appreciated by those skilled in the art upon reference to the following detailed descriptive matter in connection with the accompanying drawings disclosing what now appears to be a preferred embodiment of the invention. It is to be understood, however, that 25 the invention is capable of other mechanical expressions within the spirit and scope of the subject matter claimed hereinafter.

In the drawings,

Figure 1 is a perspective view illustrating the 30 front portion of a cotton handling machine incorporating my invention;

Figure 2 is a rear perspective view thereof;

Figure 3 is a central cross-sectional view 35 through the machine;

Figure 4 is a view in front elevation of the machine with certain parts removed and other parts broken away to more clearly illustrate the conveyor picker rolls;

Figure 5 is an end elevational view of the frame 40 with the hopper, or dirt collecting bottom and conveyor deleted;

Figure 6 is a detail view illustrating relationship of the stripper roll saw cylinder and brush roll,—the same being shown in fragmentary form with 45 the saw cylinder and brush roll in cross section and the stripper roll in elevation, and

Figure 7 is a group view illustrating medial fragmentary portions of certain of the cleaning rolls.

Referring specifically to the drawings wherein the same reference characters have been used to designate the same parts in all views, the machine comprehends a frame including spaced longitudinal sill members A, A', which are adapt- 50

ed to be supported, if desired, by a floor joist B. It is to be understood that in the usual installation the hull separator and cleaner, which is the subject of this specification, will be located considerably above the level of the gins and ordinarily in the upper or second floor of the gin house.

Connecting the sills A, A', at each end and extending laterally beyond the same are the beams 10 or cross members C from which rise the corner posts D, which are tied together at their upper ends by cross members E and longitudinal members G and K. The longitudinal frame member G is at the rear of the machine and between the 15 same and the base member C are two other longitudinal frame members H, J, which are secured at their ends to the corner posts D, as best shown in Figure 3.

At the front of the machine there are provided, 20 in addition to the upper longitudinal beam or frame member K, the longitudinal frame members or beams L, L' and M, the latter of which rests, as shown, upon the base or sill member A.

Figure 3 also shows that there is an intermediate longitudinal frame beam or member N extending between the upper cross pieces or beams E,—this member N serving to support the inner portion of the removable top closures O, which extend the full length of the machine. Removable panels, such as P, may be employed for sealing the rear side of the machine or casing.

Suitably secured beneath the sill members A, A' is a frame which extends the full length of the machine, such frame comprising longitudinal members Q connected at their ends by cross members R. This frame supports the elongated hopper-like bottom S to the lower end of which is secured the trough T carrying the rotary screw conveyor U,—it being observed that the trough T is preferably reinforced at its ends by vertical brace members V, which are suitably secured to the lower cross members C of the main frame or to the cross members Q of the sub-frame.

Suitable posts F carried by one or the other or both of the main frame cross members D, E, 45 serve to carry suitable bearings for the projecting ends of the shafts of the rotary elements which will be referred to hereinafter.

At the rear of the machine above the longitudinal frame member H and held inwardly by 50 the bracket W' is the panel W whose upper end is carried by the upper, rear longitudinal frame member G, as shown in Figure 3.

At the front of the frame and terminating short 55 of the ends thereof is the enclosure Y, which is open at its top and bottom so as to permit the cotton to be discharged thereinto from the feeder or other conveyor I when the by-pass valve 3 is in the dotted line position of Figure 3 to close the inlet opening 2 at the front of the frame. 60 When the by-pass valve or plate 3 is in the dotted line position the cotton will be discharged directly onto the gin feeding belt or conveyor, the top flight of which works in the trough or guide-way Z, as shown. Of course, normally the cotton would be fed into the separator and cleaner through the inlet opening 2, but in the case of very clean non-bolby cotton satisfactory results could be obtained by feeding the same directly to the 65 gins, thus by-passing the hull separator and cleaner.

The cotton passing into the machine sliding upon the bypass valve or plate 3, passes on to the adjustable slide plate 6, which is preferably pivoted as at 4 to the plate 5 which also pivotally

carries the bypass valve or plate 3. Adjustment of the plate 6 is had by means of the adjusting device 7, 7^a, which is pivoted to the end of the plate 6, as shown. The object of the adjustable slide or plate 6 is to enable same to be brought just the proper distance from the spaced circumferential series of saw-teeth 8^a on the saw cylinder 8 journaled upon shaft 8^b, which is carried in bearings 8^c at either end of the frame. By careful adjustment of the plate 6 it is possible 10 to permit fine trash and dirt to fall downwardly and at the same time impinge the cotton so that the teeth of the saws 8^a can get a good hold therein.

The cotton is carried by the saws 8^a in an upward direction (the saw cylinder 8 rotating in the direction of the arrow a, Figure 3), the circumferential series of V-shaped ribs 10^a on the periphery of the roll 10 which rotates in a clockwise direction, as per arrow c, throwing the burrs 15 or hulls and trash together with such cotton as remains intermixed therewith backwardly onto the conveyor roll 9 having its spikes 9^a arranged in opposite spirals so as to conduct the dirt and trash toward each end of the machine, at the 20 same time, of course, throwing the burrs, hulls and trash against the saws repeatedly so as to assure the removal of the major portion of the lint therefrom before the same drops through the openings 9^c at the ends of the trough 9^d, which 25 is disposed beneath the roll 9. It is to be observed that the trough 9^d is arranged so as to direct the hulls substantially toward the points of the teeth of the saws 8^a, so as to assure the engagement by the teeth of such lint as may remain in the 30 bolls or hulls.

The trough 9^d is secured as shown to the longitudinal board or frame member X located just above the inlet opening 2.

The hulls or bolls, discharged through the openings 9^c at the ends of the trough 9^d, fall upon the roll 17 on shaft 17^b, whose peripheral pins 17^a are arranged in opposed spirals so as to conduct the bolls and trash toward the center of the machine, while at the same time throwing them repeatedly 40 against the saws 8^a to make certain of the removal of every iota of lint from the bolls before they are discharged through the central opening in the subjacent trough 18 and into the spout 19 for discharge into the dirt chamber 20 above the 45 screw conveyor U.

The seed cotton engaged by the saws 8^a will be carried past the longitudinally V-ribbed periphery 10^a of the roll 10 to be brushed off by the brushes 11^a of the brush roll 11 of shaft 11^b, which 50 rotates in the direction of the arrow d, as shown in Figure 3. The seed cotton thus removed from the saw cylinder or roll 8 is directed upon the picker roll 12, having the picker teeth 12^a and being rigid on shaft 12^b. As shown, there is a 55 series of picker rolls or cleaner rolls, the roll 12 being the first and rolls 13, 14 the succeeding picker rolls which have, respectively, picker teeth 13^a, 14^a and are carried by shafts 13^b, 14^b, respectively. Suitably mounted beneath the picker roll 12 is the screen 12^c carried by the rear frame member H and an intermediate longitudinal bar 15, which also supports the rear edge of the screen member 13^c beneath the roller 13. This screen's 60 forward edge is supported by longitudinal bar 16. 14^c designates the screen beneath the roller 14 and this is carried by the bar 16 and the front longitudinal frame member M, as clearly shown in Figure 3.

The formation of the longitudinal V-shaped 75

ribs 10^a of roll 10 is very important, since the sides of such V-shaped ribs tend to present themselves at an angle to the cotton upon the saws 8^a, so as not to strip the cotton therefrom, but at the same

5 time to effectually throw back the hulls or bolls.

Since the spout 19, delivering the hulls and trash from trough 18 to chamber 20, is located intermediate the ends of the final cleaner cylinder 14 it is important, in order to prevent jamming, that a medial spiral array of spikes 13^a of cleaner roll 13 be arranged so as to throw the cotton endwise,—that is to say toward each end,—so that there will be a gap in the bat of cotton when the same reaches the spout 19. It is preferable also that the spikes 12^a of the roll 12 be similarly arranged at the center of the rolls as indicated at 12^a.

As is apparent, there will necessarily have to be some clearance between the spout 19 and the 20 edges of the hole in the trough 14^a through which the spout extends. Consequently, the teeth 14^a of the roll 14 within the spout are preferably spirally arranged so as to throw the trash and dirt toward the center of the spout so that none 25 will mix with the seed-cotton passing by the spout on either side thereof.

Needless to say, all of the rolls herein referred to are keyed upon their shafts, the ends of which extend through the ends of the frame and are 30 journaled in suitable bearings carried by corner posts D and intermediate vertical posts F. The pulleys, 8^c, 9^c, 10^c, 11^c, 12^c, 13^c, 14^c, are availed of to drive the respective shafts of the elements 35 designated by corresponding numerals minus the letter suffix.

The cleaning roll 14 discharges the cotton in a thin bat into the trough Z and upon the belt conveyor 21 working therein, which carries the cotton to the gins, or more accurately to the 40 feeders which in turn discharge into the gins.

A buffer 22 disposed forwardly of and above the lower hull conveyor 17 serves to intercept the hulls and trash to prevent the same from being thrown or carried upwardly along with such cotton as may be stripped from the hulls at this 45 point. The buffer 22 is carried by brackets 23 secured to the front wall portion L' by means of bolts or the like 24. Obviously, the bracket 23 can be adjusted toward or from, the saws 8^a by 50 the interposition or removal of packing 23' between the inner end of the bracket and the inner face of the carrying member L'.

The trough 18 beneath the lower hull conveyor roller 17, is supported by the frame member L at the front of the machine and its rear 55 edge by means of a bracket member 25 having an extension 25^a extending in the direction of the saws to prevent seed cotton from falling into the trough, such bracket having a portion extending 60 toward the cleaner roll 12 to make sure of the deflection of the cotton upon the upper portion of the roll 12, so that the same will be carried around the roll in a clockwise direction to form or produce a substantially flat and thin bat of cotton, 65 which renders the separation of dirt and foreign matter therefrom much easier than would be the case otherwise.

The bracket W', which supports the inwardly sloping panel W, has secured along its longitudinal edge, a panel 26 which serves to close the space between the portion W and the beam H. Bolts 27 are availed of for connecting panel 26 to bracket W' and these bolts also serve to secure the plate 28 to the inner face of such panel 26. 70 Plate 28 serves to deflect the cotton against the

screen 12^c, the inner edge of such plate projecting in the direction of the brush roll 11 to prevent cotton from being carried past the cleaning roll 12.

It is also to be observed that a channeled-shaped bar or member 30, extending the full length of the machine is secured by brackets 31 to the inner faces of the end walls of the casing adjacent the front thereof and at the top by means of bolts 32 extending through elongated slots 33. 10 This construction enables the projecting edge 39^a of said bar to be brought very close to the V-shaped ribs 10^a of the stripper roll 10 so as to prevent the bolls and trash from being carried around by roll 10. It will be understood that the 15 projecting portion 39^a of bracket 30 is relatively flexible and tends to deflect the hulls and trash in a counter clockwise direction and upon the upper conveyor roll.

It is very important to observe that the inlet 2 20 of the hull separator and cleaner is located below the upper hull conveyor roll 9 and between the same and the lower hull conveyor roll 17. The result is that loose dirt and trash coming in through the inlet 2 is enabled to drop off the end 25 of the adjustable slide plate 6 and into the trough 18 beneath the lower hull conveyor roll 17. Thus, initially, there is a considerable separation of dirt and foreign matter from the cotton. Besides this,—the hulls which are stripped from the saws 30 by the stripper roll 10, are thrown back upon the conveyor 9 above trough 9^a, so as to be segregated to all intents and purposes from the incoming cotton for presentation to the saw roll 8 while being conveyed toward each end of the trough 35 9^a. Of course, the hulls will be thrown upon the top of the cotton passing upwardly on the saws, but being upon the top of the same will be readily stripped or thrown off and thrown back upon the hull conveyor roll 40 9. It will be obvious that continual repetition of this action will remove the lint from the hulls so that there will be very little left when they finally drop through the openings 9^a at the outer ends 45 of the trough 9^a. What lint is left in the hulls will be removed by the saws during the conveyance of the hulls toward the opening of the trough 18, which discharges the material into spout 19.

Attention is further invited to the extreme 50 simplicity and compactness of the construction made possible by the arrangement of the cleaning rolls 12, 13, 14, beneath the hulling apparatus.

The casing Y is, in effect, an auxiliary casing 55 or chute through which the cotton coming into the machine may be directed immediately to the conveyor 21 when plate or valve 3 is closed against inlet opening 2. The auxiliary casing or portion Y also serves as the outlet for the 60 seed-cotton from the final cleaner roll 14. Inasmuch, as the inlet and outlet from the hull separator and cleaner apparatus is at the same side of the machine and communicates with casing Y, it provides an outlet for the material 65 whether passed through the hull separator or conveyed direct from the feeder 1 to the distributor belt 21.

Obviously, the shafts of the various rotatable elements may be adjusted by moving their bearings in the end walls of the casing so as to suit requirements and produce the best results. Adjustment of shafts is a common expedient and therefore no necessity for illustrating same here is seen.

As illustrated in the detail view, Figure 7, the intermediate portions of the rolls 12, 13 have spikes 12^a, 13^a arranged in opposed spiral series for conducting the seed-cotton laterally to either side of the spout 19, as intimated hereinbefore.

Suitable closures of a removable nature, and which are indicated at P may be disposed at the front and rear of the frame, the former at either side of the casing Y and the latter between the members H and G.

Having thus described my invention, what I claim as new and desire to secure by Letters Patent is:

15. 1. The combination of a hull separator and cleaner for cotton comprising a casing having an inlet, a driven saw cylinder against which said inlet discharges, means for stripping the hulls from the saw cylinder, a picker roll above said inlet and receiving the hulls from said stripping means, said picker roll having means for conveying the hulls toward each end of the casing in contact with the saw cylinder and maintaining the separated hulls above the incoming cotton, a second picker roll in said casing below said inlet and receiving the hulls from said upper picker roll, said lower picker roll having means for conveying the hulls in contact with the saws toward the center of the casing, a trough beneath said second picker roll and having a discharge opening intermediate its ends, a discharge spout leading from said trough opening, and cotton cleaning means in said casing to which the seed-cotton is delivered from said saw cylinder.
20. 2. The combination of a hull separator and cleaner for cotton comprising a casing having an inlet, a driven saw cylinder against which said inlet discharges, means for stripping the hulls from the saw cylinder, a picker roll above said inlet and receiving the hulls from said stripping means, said picker roll having means for conveying the hulls toward each end of the casing in contact with the saw cylinder, a second picker roll in said casing below said inlet and receiving the hulls from said upper picker roll, said lower picker roll having means for conveying the hulls in contact with the saws toward the center of the casing, a trough beneath said second picker roll and having a discharge opening intermediate its ends, a discharge spout leading from said trough opening, and cotton cleaning means in said casing to which the seed-cotton is delivered from said saw cylinder.
25. 3. The combination of a hull separator and cleaner for cotton comprising a casing having an inlet, a driven saw cylinder against which said inlet discharges, means for stripping the hulls from the saw cylinder, a picker roll above said inlet and receiving the hulls from said stripping means, said picker roll having means for conveying the hulls toward each end of the casing in contact with the saw cylinder, a second picker roll in said casing below said inlet and receiving the hulls from said upper picker roll, said lower picker roll having means for conveying the hulls in contact with the saws toward the center of the casing, a trough beneath said second picker roll and having a discharge opening intermediate its ends, a discharge spout leading from said trough opening, and cotton cleaning means in said casing to which the seed-cotton is delivered from said saw cylinder, and said cotton cleaning means having means for discharging the cleaned cotton at either side of said spout.
30. 60. 4. The combination of a hull separator and cleaner for cotton comprising a casing having an inlet, a driven saw cylinder against which said inlet discharges, means for stripping the hulls from the saw cylinder, a picker roll above said inlet and receiving the hulls from said stripping means, said picker roll having means for conveying the hulls toward each end of the casing in contact with the saw cylinder, a second picker roll in said casing below said inlet and receiving the hulls from said upper picker roll, said lower picker roll having means for conveying the hulls in contact with the saws toward the center of the casing, a trough beneath said second picker roll and having a discharge opening intermediate its ends, a discharge spout leading from said trough opening, and cotton cleaning means in said casing to which the seed-cotton is delivered from said saw cylinder, said casing having a seed-cotton outlet beneath said inlet and extending to either side of said spout, and said cleaning means having discharge means for diverting the cotton to either side of said spout.
35. 65. 5. In a hull separating and cleaning machine for cotton, having a cotton inlet and separate hull and seed cotton outlets, hull separating means adjacent said inlet, seed cotton cleaning means including driven cleaner rolls disposed beneath said hull separating means, a hull discharge spout extending across the path of the outgoing seed cotton, means on certain of said cleaning rolls for diverting the outgoing seed cotton past said spout.
40. 70. 6. In a hull separating and cleaning machine for cotton, having a cotton inlet and separate hull and seed cotton outlets, hull separating means adjacent said inlet, seed cotton cleaning means including driven rolls disposed beneath said hull separating means, a hull discharge spout extending across the path of the outgoing seed cotton, means on certain of said cleaning rolls for diverting the outgoing seed cotton past said spout, one of said cleaning rolls extending transversely through said spout, and means on such roll for conveying the hulls centrally of said spout.
45. 75. 7. In a hull separator and cleaner for cotton, hull and seed cotton separating means, a hull discharge spout, and cleaning means including a driven roll extending transversely through the spout and said roll having means for conveying the seed cotton past the sides of said spout.
50. 80. 8. In a hull separator and cleaner for cotton, hull and seed cotton separating means, a hull discharge spout, cleaning means including a driven roll extending transversely through the spout and said roll having means for conveying the seed cotton past the sides of said spout, and conveyor means on said roll within said spout for actuating the hulls away from the spout sides.

means for conveying the hulls in contact with the saws toward the center of the casing, a trough beneath said second picker roll and having a discharge opening intermediate its ends, a discharge spout leading from said trough opening, cotton cleaning means in said casing extending beneath said saw cylinder and to which the seed-cotton is delivered from said saw cylinder.

4. The combination of a hull separator and cleaner for cotton comprising a casing having an inlet, a driven saw cylinder against which said inlet discharges, means for stripping the hulls from the saw cylinder, a picker roll above said inlet and receiving the hulls from said stripping means, said picker roll having means for conveying the hulls toward each end of the casing in contact with the saw cylinder above and in substantial separation from the incoming cotton, a second picker roll in said casing below said inlet and receiving the hulls from said upper picker roll, said lower picker roll having means for conveying the hulls in contact with the saws toward the center of the casing, a trough beneath said second picker roll and having a discharge opening intermediate its ends, a discharge spout leading from said trough opening, cotton cleaning means in said casing extending beneath said saw cylinder and to which the seed-cotton is delivered from said saw cylinder, said casing having a seed-cotton outlet beneath said inlet and extending to either side of said spout, and said cleaning means having discharge means for diverting the cotton to either side of said spout.

5. In a hull separating and cleaning machine for cotton, having a cotton inlet and separate hull and seed cotton outlets, hull separating means adjacent said inlet, seed cotton cleaning means including driven cleaner rolls disposed beneath said hull separating means, a hull discharge spout extending across the path of the outgoing seed cotton, means on certain of said cleaning rolls for diverting the outgoing seed cotton past said spout.

6. In a hull separating and cleaning machine for cotton, having a cotton inlet and separate hull and seed cotton outlets, hull separating means adjacent said inlet, seed cotton cleaning means including driven rolls disposed beneath said hull separating means, a hull discharge spout extending across the path of the outgoing seed cotton, means on certain of said cleaning rolls for diverting the outgoing seed cotton past said spout, one of said cleaning rolls extending transversely through said spout, and means on such roll for conveying the hulls centrally of said spout.

7. In a hull separator and cleaner for cotton, hull and seed cotton separating means, a hull discharge spout, and cleaning means including a driven roll extending transversely through the spout and said roll having means for conveying the seed cotton past the sides of said spout.

8. In a hull separator and cleaner for cotton, hull and seed cotton separating means, a hull discharge spout, cleaning means including a driven roll extending transversely through the spout and said roll having means for conveying the seed cotton past the sides of said spout, and conveyor means on said roll within said spout for actuating the hulls away from the spout sides.

THADDEUS S. GRIMES.
